UNITED STATES PATENT OFFICE.

DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW JERSEY.

MATRIX-DISTRIBUTING MECHANISM.

1,174,609.

Specification of Letters Patent.

Patented Mar. 7, 1916.

Application filed June 15, 1914. Serial No. 845,085.

To all whom it may concern:

Be it known that I, DAVID PETRI-PALMEDO, a citizen of the United States, residing at Bridgeport, in the county of Fairfield and 5 State of Connecticut, have invented a certain new and useful Improvement in Matrix-Distributing Mechanism, of which the following is a full, clear, and exact description.

10 Several prior patents disclose multiple magazine typographic machines which are provided with means designed to automatically distribute, to the magazines in which they belong, matrices which are constructed 15 with font distinguishing characteristics that coöperate with said distributing means to produce this result. But in all such machines, any given font of matrices will, of necessity, be distributed to the magazine 20 which occupies a certain position in the machine,—that is to say, a position which is associated with and determined by the said font distinguishing structural characteristics 25 of said matrices. In other words, a magazine which contains a font of matrices having certain distinguishing structural characteristics, must always occupy a definite position in a machine which is organized to co-operate with said structural characteristics 30 of the matrices to determine and effect their distribution. This imposes restrictions upon the use of a font of matrices and consequently upon the use of the multiple magazine machine to which they are adapted, 35 which is sometimes very objectionable. For example, a printer may have a favorite font of matrices which he desires to use in his machine in conjunction with numerous other fonts of matrices. But if this favorite font 40 be constructed for distribution to a magazine occupying a certain position in the machine, he cannot use it in conjunction with another font which is also constructed for distribution to a magazine occupying the 45 same position.

The object of this invention is to endow the distributing mechanism of a multiple magazine typographical machine with the capacity to so distribute the matrices of a 50 given font, constructed for coöperation with said distributing mechanism, that said matrices will be delivered into their own magazine, whether that magazine occupies either of several positions in the machine.

The invention is shown in a form adapted especially for use in connection with the multiple magazine typographical machine which forms the subject matter of an application Serial No. 795,398, filed by myself and E. S. Goddard October 16, 1913. The adaptation of the invention to this particular machine, fortunately, involves very slight structural changes in said machine, and very slight changes in the matrices to transform normal matrices to specialized 65 matrices, *i. e.*, matrices adapted to be distributed at will into either of two or more magazines. In fact, the changes in the machine construction required are so slight that it has not been thought necessary to 70 show any considerable part of the distributing mechanism, except the parts which involve said changes. As will be seen from the appended claims, however, the invention is much broader than its mere application 75 to this particular machine.

Any embodiment of the distributing mechanism which forms a part of the typographic machine which is shown and described in said prior application involves 80 the provision of numerous groups of switch gates. The number of such groups required depends upon the number of magazines in the machine and the number of channels in each magazine. In a machine in which, like 85 that shown in said application, there are four magazines, each adapted to contain one complete font of matrices, nine groups of gates are required. The two lower groups are those which determine which of the 90 magazines the matrices shall go into. Associated with each group of gates is a pair of endwise movable feeler rods, which are the matrix engaging parts of the gate operating mechanism; and these several pairs of feeler 95 rods are so grouped that any matrix which is moved in a fixed path toward their ends by the mechanism heretofore provided for so moving the matrices, may engage and move any desired combination of such rods, depending upon the differentiated structural characteristics of said matrices. A normal matrix, *i. e.*, a matrix which is constructed solely for use in the machine of such prior application is hole-punched in such wise that 100 it presents a hole in alignment with one or the other rod of each pair of feeler rods. Wherefore, when such a matrix is moved 105

against the ends of the group of rods, it may move one, and only one of each pair of rods,—the other rods of said pairs of rods being free to move in the reverse direction through the opposed holes in the matrix.

Each pair of feeler rods is associated with a group of switch gates through intermediate mechanism by which said group of 10 switch gates is caused to move in one direction or the other, depending upon which rod of the associated pair of feeler rods is moved by contact from said matrix.

The two upper pairs of feeler rods are 15 those which control the operation of the two lower groups of switch gates,—that is those groups which determine the magazine into which a matrix shall be delivered. In the construction shown in said application the 20 movement by pressure from a matrix of the rear feeler rod of next to the upper pair of rods, *i. e.* the eighth pair, will cause a forward movement of the gates of the next to the lower groups of gates, *i. e.*, the eighth group 25 of gates. Wherefore said gates, after being so moved, will cause any matrix to pass behind them and therefore into one or the other of the two rear magazines; whereas, if it is the front feeler rod of said pair which is so 30 moved by pressure from a matrix, the corresponding group of gates will be caused to swing rearward and thereby direct the matrices in front of them, and therefore into one 35 or the other of the two front magazines. If the rear feeler rod of the upper pair or ninth 40 pair of feeler rods is moved by pressure from a matrix, the lower or ninth group of gates will swing forward; but, if the front feeler rod of said pair is so moved, the lower 45 group of gates will swing rearward. In the former case, matrices which were delivered in front of the gates of the eighth group, 50 will be directed into the front magazine of the front pair.—that is to say, into the first magazine. Whereas those matrices which 55 were delivered toward one of the two rear magazines of the eighth group of gates will be directed into the front magazine of that pair, namely, the third magazine. In case the ninth group of gates are swung forward, 60 the matrices will be directed toward the second or fourth magazine, according as they were directed in front of or behind the gates of the eighth group.

Now, in all of the respects above pointed out a machine embodying the present invention is or may be exactly like the machine of said prior application. In fact, the drawings forming a part of this application have 65 been constructed upon the assumption that the invention is to be embodied in the machine shown in said prior application, and that all parts of the distributing mechanism required in a typographic machine, which are not shown in the present drawing, are

exactly like the machine of said prior application. It is, in fact, only necessary to change said machine in the following particulars, *viz.* one or the other or both of the two upper pairs of feeler rods, instead of 70 being supported in immovable guideways, as shown in said prior application, are supported in a housing or housings which is or are movable in a direction transversely to the length of said rods, so that the ends of 75 said rods which are adjacent to the matrices and therefore subject to the engagement thereby, may be alined with different parts of the surface of said matrices when the latter are moved toward the ends of said rods 80 by such mechanism as has heretofore been used for so moving said matrices.

In the drawing, Figure 1 is a front elevation of so much of a multiple magazine typographic machine as is concerned with the 85 present invention. Fig. 2 is a plan view partly sectioned of the mechanism shown in Fig. 1. Fig. 3 is a view from the left end of the group of feeler rods shown in Fig. 1. Fig. 4 is an enlarged plan view of the feeler rods and the mechanism by which a matrix is caused to operate them, and also of the mechanism by which the feeler rod housings are moved. Fig. 5 is a vertical sectional view in the plane of line 5—5 on Fig. 4. Fig. 6 is a side elevation of a normal matrix. Figs. 7, 8 and 9 are similar views of the upper part of three different forms of specialized matrices, adapted to be used in connection with the invention.

Referring to the parts by letters, 9^A, 9^B, represent the two rods of the upper pair, *i. e.* the ninth pair of feeler rods, namely, those feeler rods which, as shown in said prior application, are associated with and control 105 the operation of the lower or ninth group of switch gates.

8^A, 8^B represent the next to the upper, or eighth pair of feeler rods, *viz.* those which, as shown in said prior application, are associated with next to the lower or eighth group 110 of switch gates.

In the construction shown in the drawing each of the two upper pairs of feeler rods are mounted in a movable housing. The upper pair 9^A, 9^B are mounted in the housing 10, while the pair of feeler rods 8^A, 8^B are mounted in the housing 12. Each housing is merely a flat bar containing 115 guideways for the associated pair of feeler rods in which the latter are held in parallel relations, and in such manner that they may move endwise in the housing. The housing 12 rests upon the frame member 14, in which, as shown in said prior application, the seven lower pairs of feeler rods are 120 movably mounted. The housing 10 rests upon the housing 12, and both of these housings are pivoted at their right ends to the frame member 14 on the same vertical 125 130

5 pivot 15 and are independently movable. This manner of mounting the housings permits the left ends thereof, namely, the ends from which the feeler rods project for engagement with the matrices, to be moved short distances forward and backward,—that is to say, in directions transverse to the length of said feeler rods, whereby said feeler rods may become alined with different parts of a matrix, when the latter is held in 10 a cage 16 which is movable in a fixed path toward and from the adjacent ends of the feeler rods, by suitable mechanism. It is sufficient for the present purposes to know that this cage is fixed to a slide 16^a which is movable horizontally in fixed guideways; inasmuch as this cage and its associated mechanism is shown and described in detail 15 in Letters Patent No. 921,065.

20 There is associated with each housing a spring 17 which operates to move said housing forward, into the special position therefor, when it is permitted so to act. When so moved, said housings are stopped in the 25 proper special positions by engagement with set screws 18 or 19. Associated respectively with said housings 10 and 12 are the cams 25, 26, pivoted to the frame of the machine. Each of these cams is independently movable, and when suitably moved will engage 30 the associated housing and move it back to normal position and hold it there.

35 Associated with the two housings are the two levers 30 and 31. The right end of the former engages in a recess 10^a in the upper housing. The right end of the latter engages a similar recess in the lower housing. Pressure applied to the rear side of the left end of either of these levers will cause the lever 40 to swing and the associated housing to move rearward into its normal position.

Fig. 6 represents a normal matrix which is constructed with differentiating structural characteristics for coöperating with the distributing mechanism when both of the two upper pairs of feeler rods are in their normal or rearmost position. That is to say, said matrix is hole-punched in such a manner that when it is moved against the ends 50 of the feeler rods, when the latter are in their normal positions, it will engage and move the rear rod of the upper pair and the front rod of the eighth pair. In a machine constructed as shown in said prior application this will cause such movements of 55 the eighth and ninth groups of switches that the matrix will be guided into the second magazine.

60 Figs. 7, 8 and 9 each show a specialized matrix which has the same fcnt distinguishing structural characteristics as the matrix shown in Fig. 6, whereby under the conditions stated each of said matrices may be delivered into the second magazine. But 65 each of the matrices shown in Figs. 7, 8

and 9 has other font distinguishing structural characteristics, through the action of which on the eighth and ninth pairs of feeler rods there will result such a movement of the eighth and ninth groups of 70 switches as will cause the matrix to be delivered into some other magazines.

On each of Figs. 6 to 9 are four vertical lines *a*, *b*, *c* and *d*, and two horizontal lines *e* and *f*. The points 9^a and 9^b at which the 75 line *e* intersects lines *a* and *b* are the points which are alined with the two upper feeler rods when the housing 10 therefor is in its normal, *i. e.* its rear position. Therefore, at one or the other of these points a hole 80 must be punched, so that the matrix may be slipped over the end of one feeler rod of the ninth pair, and will not therefore press against more than one of said feeler rods when the housing therefor is in the rearmost 85 position. In all of said Figs. 6 to 9 the hole is punched at the point 9^a.

The points 8^a, 8^b at which lines *a*, *b*, intersect line *f*, are the points which are alined with the eighth pair of feeler rods, when the 90 housing 12 which carries them is in its normal, that is its rear position. Therefore, a hole must be punched at one or the other of these points in order that the matrix may selectively move one or the other of said 95 rods as it is moved against them, when housing 12 is in its normal position. When, therefore, the two housings 10 and 12 are both in their normal positions, all of the matrices shown in these four figures will 100 produce the same selective characteristic movements of the eighth and ninth pairs of feeler rods,—that is to say, such movements as will produce, in a machine like that shown in said prior application, a movement 105 of the eighth and ninth groups of gates such as will cause the matrices to be delivered into the second magazine.

The points 9^c, 9^d at which line *e* intersects lines *c* and *d* are the points which are alined with the ninth pair of feeler rods when their housing 10 is in its forward or special position. Therefore a hole must be made at one or the other of these points if the matrix is to be capable of selectively 110 moving the ninth pair of feeler rods when their housing 10 is in its forward or special position.

The points 8^c, and 8^d at which line *f* intersects lines *c* and *d*, are the points which are alined with the eighth pair of feeler rods when the housing 12 which carries them is in its forward position. Therefore, a hole must be made at one of these points, if the matrix is to be capable of selectively operating 115 the eighth pair of feeler rods when the housing 12 therefor is in its forward position.

Fig. 7 shows a matrix which is specialized 120 by the addition to a matrix like that shown 125

in Fig. 6, of a specializing hole at the point 9^d. If, therefore, the housing 10 is in its forward position, this matrix, when moved against the feeler rods, will move the front 5 rod of the upper pair instead of the rear rod of said pair, as it would if the housing 10 were in its normal position. The provision, therefore, of the specializing hole at 9^d may cause such movement of the ninth group of 10 gates that this matrix will be guided into the first magazine.

The matrix shown in Fig. 8 is not only the same normal arrangement of holes which are shown in Fig. 6, but it also has a specializing hole at 8^e. Therefore, when the housing 12 is in its forward position the rear feeler rod of the eighth pair will be engaged and moved by the matrix instead of the front rod of said pair, as would be the 20 case if the housing 12 were in its rear position. Therefore by having the housing 12 in special forward position when this matrix is moved against the feeler rods, there will result such a movement of the 25 eighth and ninth groups of gates in the machine as shown in said application that the matrix will be guided into the fourth magazine.

In the matrix shown in Fig. 9 there are 30 the same arrangement of holes which is characteristic of the matrix shown in Fig. 6, and there are also specializing holes at the points 9^d and 8^e for coöperation with the feeler rods of the eighth and ninth pair of 35 rods when both of the housings 10 and 12 are in their forward positions. If, under such conditions, this matrix is moved against the feeler rods, there will be such a selective movement thereof and a consequent 40 movement of the eighth and ninth groups of switch gates in the machine shown in said prior application, that the matrix will be delivered into the third magazine. In fact, the doubly specialized matrix shown in 45 Fig. 9 may cause such selective operations of the eighth and ninth pairs of feeler rods as will cause the deliverance of such matrix into any one of the four magazines at will. If, for example, the housing 10 is locked 50 back in its normal or rearward position by the action of the cam 25 the normally placed hole on this matrix will coöperate with the ninth pair of feeler rods and a specializing hole will coöperate with the eighth pair of 55 feeler rods, which will result in such selective operation of said feeler rods and the associated groups of switch gates that the matrix will be guided into the fourth magazine. If only the housing 12 is locked back 60 in its rearmost position by the action of the cam 26, the matrix will be delivered into the first magazine; while if both housings are locked back by the cams provided for that purpose, only the normally placed holes 65 will coöperate with the two upper pairs of

feeler rods, and consequently this matrix will be guided normally and delivered into the second magazine.

The machine shown and the matrices shown are constructed for such coöoperative action that each matrix requiring such movement may automatically move one or both housings 10 and 12 rearward in opposition to springs 13, so that when any matrix engages the feeler rods, said housings 75 will be in the required positions for distributing either normal matrices into the magazines in which they belong, or for distributing the specialized matrices into magazines occupying the special positions for 80 which the matrices are specialized. For example, if the machine contains magazines holding normal matrices and some or all of the specialized varieties shown in Figs. 7, 8 and 9, the two housings 10 and 12 may be 85 allowed to be moved by their springs to their special or forward positions. In that event, both ends of the levers 30 and 31 will project into the path of the front edges of all the matrices. In the front edges of the 90 specialized matrices are notches 20^a which are so placed as to enable the matrices to pass one or both of said levers, as required, without moving the same. A normal matrix has no such notch, and therefore as it 95 is moved toward the feeler rods, it engages and rocks both levers 30 and 31, and consequently moves both housings rearward into the positions they should occupy to produce the desired coöoperative action between the eighth and ninth pairs of feeler 100 rods and the structural font distinguishing characteristics of the normal matrix. If, however, a matrix is specialized as shown in Fig. 7 for coöperation with the feeler 105 rods of the housing 10 when in its forward position, and the housing 12 when in its rear position, this notch 20^a is so constructed and located in the front edge of the matrix that such edge will not engage the upper 110 lever 30, but will engage and rock the lower lever 31. When the matrix is specialized as shown in Fig. 8, the notch 20^a is located so that the front edge of the matrix will engage and move the upper lever 30, but 115 will not engage the lower lever 31. Therefore, the lower housing will remain in the abnormal position and the upper housing 120 will be moved to the normal position.

When the matrix like that shown in Fig. 120 9 is specialized for coöperation with the two upper pairs of feeler rods when both housings 10 and 12 are in their forward positions, the notch is made so wide that the front edge of the matrix does not engage 125 either levers 30 or 31.

When only normal matrices are being used in the machine both housings 10 and 12 may be moved and held in the rear position by the action thereon of the cams 130

and 26. When none of the matrices being used in the machine is specialized so as to require that either of the housings 10 or 12 be in its forward position, said housing 5 may be locked in its normal position by the associated cam, and the other one allowed to be moved forward by its spring.

Having described my invention, I claim:

1. In a typographic machine containing 10 matrix distributing mechanism, the combination with said distributing mechanism, of a matrix having plural sets of differentiating structural characteristics, each set being adapted to independently coat with the 15 same parts of said distributing mechanism to produce characteristically different matrix distributing results.

2. In a typographic machine containing 20 matrix distributing mechanism, the combination with certain matrix engaging members of said distributing mechanism, of a matrix having plural sets of structural characteristics adapted to independently co-operate with the same matrix engaging 25 members, and means for causing either but only one of said sets of structural characteristics of the matrix to coat with said matrix engaging members and to thereby produce characteristic distributing results.

3. In a multiple magazine typographic 30 machine containing distributing mechanism, the combination of magazine determining parts of said distributing mechanism, a matrix having plural sets of magazine determining structural characteristics adapted to 35 independently co-operate with said magazine determining parts of said distributing mechanism to cause the matrices to be delivered into different magazines, and means 40 for causing either of said sets of magazine determining structural characteristics of the matrix to co-operate with said magazine determining parts of said distributing mechanism.

4. In a multiple magazine typographic 45 machine containing matrix distributing mechanism, the combination with certain matrix engaging members of the magazine determining part of the distributing mechanism, of a matrix having plural sets of magazine distinguishing structural characteristics adapted to independently co-operate with said matrix engaging members to produce characteristically different matrix distributing results, and means for causing 50 said matrix engaging members to coat with either set of magazine distinguishing structural characteristics of said matrix.

5. In a multiple magazine typographic 60 machine containing matrix distributing mechanism, the combination with certain movable matrix engaging members of the magazine determining part of said distributing mechanism, of a matrix having plural 65 sets of magazine distinguishing structural

characteristics, each set being adapted to selectively coat with the same matrix engaging members of the distributing mechanism to produce characteristic movements thereof and consequently characteristic distributing 70 results, and means for causing either set of said structural characteristics of the matrix to selectively coat with the said matrix engaging members of the distributing mechanism. 75

6. In a typographic machine containing distributing mechanism, the combination of certain matrix engaging parts of said mechanism, a matrix having plural sets of differentiating structural characteristics adapted 80 to independently co-operate with said matrix engaging members to produce characteristically different matrix distributing results, means for moving said matrix in a definite path into co-operative engagement 85 with said members, and means for changing the position of said matrix engaging members with respect to the path through which said matrix is moved and to thereby bring them into the required position for co-operation 90 with either set of structural characteristics of the matrix.

7. In a multiple magazine typographic machine containing matrix distributing mechanism, the combination of two sets of 95 matrix engaging members of said distributing mechanism, a matrix provided with plural sets of structural characteristics associated with each set of matrix engaging members, means for moving the matrix in 100 a fixed path toward said matrix engaging members, means for independently moving the two sets of matrix engaging members into different position with respect to said path in which the matrix is moved. 105

8. In a multiple magazine typographic machine containing distributing mechanism, the combination of certain matrix engaging members of the magazine determining part of said distributing mechanism, with means for moving matrices in a fixed path into co-operative engagement with said members, means for changing the position of said members with respect to the path in which the matrices are so moved, and a set 110 of matrices each having two sets of structural characteristics adapted to selectively co-operate with said matrix engaging members according as said members are in one or the other of the positions they may occupy 115 in respect to the path in which said matrices move. 120

9. In a typographic machine, containing matrix distributing mechanism, the combination of certain movable matrix engaging 125 members of said mechanism, which members are capable of occupying either of two positions in respect to the path in which the matrices are moved, means for moving matrices in a fixed path into selective engage- 130

ment with said members, a spring yieldingly holding said members in one of the two positions they may occupy with respect to the path in which the matrices are moved, and means, adapted to be operated by the matrices as they are moved along said path, for moving said matrix engaging members into the other of the positions they may occupy with respect to the path in which the matrices move.

10 10. In a typographic machine containing matrix distributing mechanism, the combination of certain movable matrix engaging members of said mechanism, which members are capable of occupying either of two positions in respect to the path in which the matrices are moved, means for moving matrices in a fixed path into selective engagement with said members, means adapted to be operated by the matrices as they are moved along said path for moving said matrix engaging members into the other of the positions they may occupy with respect to the path in which the matrices move, and matrices, some of said matrices having only one set of structural characteristics adapted to selectively engage and move said members, and other matrices having two sets of structural characteristics adapted to independently engage said members according as the members are in one position or the other, a spring for moving said members into one of the two positions specified, mechanism for moving said members into the other of said two positions, and means on one of the two kinds of matrices mentioned for actuating the last mentioned mechanism.

11 11. In a typographic machine containing matrix distributing mechanism, the combination of a pair of endwise movable feeler rods which are matrix engaging members of a part of said distributing mechanism, a housing in which said rods are movably mounted, which housing is movable with respect to the path in which the matrices are moved for engagement with said feeler rods, means for moving the matrices in a fixed path into selective engagement with said feeler rods, and means for holding said housing in either of two positions in respect to the path in which the matrices are moved.

12 12. In a typographic machine containing matrix distributing mechanism, the combination of a pair of endwise movable feeler rods which are matrix engaging members of a part of said distributing mechanism, a housing in which said rods are movably mounted, which housing is movable with respect to the path in which the matrices are moved for engagement with said feeler rods, means for moving the matrices in a fixed path into selective engagement with said feeler rods, matrices of which some have and some have not notches in their edges, and means adapted to be engaged by the

unnotched matrices for moving said housing into one of the positions it may occupy, and a spring for yieldingly holding said housing in the other of said positions.

13 13. In a typographic machine containing matrix distributing mechanism, the combination of a pair of endwise movable feeler rods which are the matrix engaging members of a part of said distributing mechanism, a housing in which said rods are movably mounted, which housing is movable with respect to the path in which the matrices are moved for engagement with said feeler rods, means for moving the matrices in a fixed path into selective engagement with said feeler rods, means for holding said housing in one of two positions it may occupy, a spring adapted, when permitted so to do, to move the housing into the other of the two positions it may occupy, and means adapted to be engaged by certain matrices for moving said housing in opposition to said spring into the first named position.

14 14. In a multiple magazine typographic machine containing matrix distributing mechanism, the combination of two pairs of feeler rods which are the matrix engaging members of the magazine determining parts of said distributing mechanism, means for moving matrices in a fixed path to cause them to selectively engage said feeler rods, two housings in each of which a pair of said feeler rods are movably mounted, which housings are independently movable with respect to the path in which the matrices are moved, and matrices which are provided with plural sets of structural characteristics associated with and adapted to selectively engage each pair of feeler rods according to the positions in which said housings may be.

15 15. In a multiple magazine typographic machine containing matrix distributing mechanism, the combination of two pairs of feeler rods which are the matrix engaging members of the magazine determining parts of said distributing mechanism, means for moving the matrices in a fixed path to cause them to selectively engage said feeler rods, two housings in each of which a pair of said feeler rods are movably mounted, which housings are independently movable with respect to the path in which the matrices are moved, and matrices which are provided with plural sets of structural characteristics associated with and adapted to selectively engage each pair of feeler rods according to the positions in which said housings may be, a spring associated with each housing and adapted to yieldingly hold it in one of the two positions it may occupy with respect to the path in which the matrices are moved, and means adapted to independently hold each of said housings in the other position which it may occupy.

16. In a multiple magazine typographic machine containing matrix distributing mechanism, the combination of two pairs of feeler rods which are the matrix engaging members of the magazine determining parts of said distributing mechanism, means for moving matrices in a fixed path to cause them to selectively engage said feeler rods, two housings in each of which a pair of said feeler rods are movably mounted, which housings are independently movable with respect to the path in which the matrices are moved, and matrices which are provided with plural sets of structural characteristics associated with and adapted to selectively engage each pair of feeler rods according to the positions in which said housings may be, a spring associated with each housing and adapted to yieldingly hold it in one of the two positions it may occupy with respect to the path in which the matrices are moved, means adapted to independently hold each of said housings in the other position which it may occupy, and means adapted to be engaged and moved by certain matrices for automatically moving said housings independently into the last named position.
17. In a multiple magazine typographic machine containing matrix distributing mechanism, the combination of a pair of endwise movable feeler rods, a pivoted housing in which said rods are mounted for independent endwise movement, mechanism for moving matrices in a fixed path to cause them to selectively engage said feeler rods, a spring yieldingly holding said housing in one of two positions it may occupy with respect to the path in which the matrices are moved, a stop limiting the spring induced movement of the housing, means limiting the movement of the housing in the opposite direction, and means for holding said housing in engagement with the last mentioned stop.
18. In a multiple magazine typographic machine containing matrix distributing mechanism, the combination of a pair of endwise movable feeler rods, a pivoted housing in which said rods are mounted for independent endwise movement, mechanism for moving matrices in a fixed path to cause them to selectively engage said feeler rods, a spring yieldingly holding said housing in one of two positions it may occupy with respect to the path in which the matrices are moved, a stop limiting the spring induced movement of the housing, means limiting the movement of the housing in the opposite direction, and means for holding said housing in engagement with the last mentioned stop.

Copies of this patent may be obtained for five cents each, by addressing the "Commissioner of Patents, Washington, D. C."
